UNITED STATES PATENT OFFICE.

ISAAC R. CURTIS, OF NEWARK, NEW JERSEY.

IMPROVEMENT IN SUSPENDERS.

Specification forming part of Letters Patent No. 149,727, dated April 14, 1874; application filed December 24, 1872.

To all whom it may concern:

Be it known that I, ISAAC R. CURTIS, of Newark, in the county of Essex and the State of New Jersey, have invented new and useful Improvements in Suspenders; and I do hereby declare that the following specification, taken in connection with the drawings furnished, is a full, clear, and exact description thereof, which will enable others skilled in the art to make and use the same.

My invention relates to the elastic part of a suspender, which may be or is usually secured between the button-stirrups and shoulder-straps, either at the front part or behind, or both; and it consists of a coiled metallic spring inclosed within an elastic woven covering, which serves the additional purpose as a check to prevent overstretching, and at the same time yields easily and uniformly to the desired extent. The object of my invention is to furnish a cheap and lasting suspender, the embodiment of effectiveness, dispensing with rubber and similar gums, which so soon fail to perform the required functions, owing to the fact of the peculiar action of the atmosphere upon them. Suspenders made elastic by the use or employment of rubber, when packed, even in small quantities, during summer months, become inoperative in consequence of the partial melting, &c., of the small strings of the latter material, while the extreme cold abstracts the particles of liquid or soft parts, and leaves the body brittle, which readily breaks when put in use. These facts are conceded by the largest dealers in such articles, while the consumer will readily acknowledge that, even when warm and kept in contact with the human body with nearly a uniform heat, they soon become overstretched or set, and consequently fail to serve the desired purpose. For these or the foregoing reasons I have devised a means consisting of a spiral or coiled metallic spring, which may be made very small, inclosing it closely with a loose woven or elastic fabric, admitting the required action of the spring, and serving to shield the latter from the clothing, as well as forming the only means required to prevent overstretching. As these springs are generally made of brass wire or non-corrosive metal, it will be obvious to those skilled in the art that the action of the atmosphere will

not affect them to any perceptible degree. Consequently they may be packed and retained on the shelves of the manufacturer and merchant for years without injury to them. My invention differs from those suspenders wherein metallic springs of a zigzag formation are adopted. The latter necessarily have to be formed of a heavier wire, and their shape is such as to require more breath of space. They also require a rigid case or socket for protection, as well as an additional means to prevent overstretching. The stitching and other work upon them is such as to make them expensive and unmerchantable. This will also apply in those cases where series of small springs are adopted and connected together within a rigid socket.

Referring to the drawings, Figures 1 and 2 represent a part of a suspender embodying my improvement.

I employ the usual materials in the manufacture of the strap which passes over the shoulders. The usual slide or buckle for adjusting the lengths, &c., may be adopted. The coil is made in the usual way by being wound upon mandrels or otherwise, may be made in continuous lengths, and cut to suit the manufacturer; or they may be made singly of a proper length. Hard or spring brass wire is generally preferred, although other suitable metals will serve instead. Loops are formed at each end of the coil, for the purpose of connecting the stirrup and shoulder-straps or slide, which may be done by stitching, riveting, or otherwise.

The elastic covering may be braided or woven of a suitable size to inclose the metallic spring within, as shown. This is generally woven in long lengths, and cut into the desired strips, corresponding with the springs which they are to inclose.

Having thus set forth my invention, I do not claim, broadly, the employment of metallic springs; neither do I claim the elastic fabric; but the combination of a single spiral spring and an elastic inclosing-case of knitted or woven fabric, serving as a covering and the only tension necessary to prevent overstretching, the whole applied to the stirrups or shoulder-straps of a pair of suspenders, thereby forming an improved article of manufacture, I am

not aware as having been produced before my invention, as herein described; therefore,

What I claim as my invention is—

In combination with the stirrup or shoulder strap of a suspender, a button-strap or connecting-piece composed of a metallic spiral spring, B, and an elastic inclosing-case, A, of

knitted or woven fabric, substantially as and for the purpose described.

ISAAC R. CURTIS. [L. S.]
